UNITED STATES PATENT OFFICE.

FEDKO FEDZYNA, OF NEW YORK, N. Y.

SWIMMING APPARATUS.

1,320,540.

Specification of Letters Patent.

Patented Nov. 4, 1919.

Application filed November 20, 1918. Serial No. 263,253.

To all whom it may concern:

Be it known that I, FEDKO FEDZYNA, a citizen of Russia, residing at New York, county of New York, and State of New

5 York, have invented certain new and useful Improvements in Swimming Apparatus, of which the following is a specification.

This invention relates to improvements in 10 devices for assisting swimmers in propelling themselves through the water.

The principal object of the invention is to provide a cushioned inflatable float upon 15 which the swimmer may partially rest, and manually operable means whereby the laterally extending paddles are operated so as to advance the apparatus through the water.

A further object is to provide a device of 20 the class described which is operable in an easy manner and which is capable of exerting a propulsive force compatible with its size.

These and other like objects are attained 25 by the novel construction and combination of parts hereinafter described, and shown in the accompanying drawings, forming a material part of this disclosure, and in which—

Figure 1 is a top plan view showing a 30 swimming apparatus made in accordance with the invention.

Fig. 2 is a vertical sectional view taken on line 2—2 of Fig. 1.

Fig. 3 is a fragmentary longitudinal sectional view, taken on line 3—3 of Fig. 5.

Fig. 4 is a side elevational view of the apparatus.

Fig. 5 is a transverse sectional view taken on line 5—5 of Fig. 4, and

40 Fig. 6 is an end view of the pneumatic cushion device used in connection with the structure.

Referring to the drawings, the apparatus will be seen to comprise a saddle shaped 45 block 10, preferably made of wood, having a narrow front extending portion 11. The upper portion of the block is formed with a concave upper surface 12, extending longitudinally of the apparatus.

50 Secured in the upper portion and at the widest part of the saddle element 10, are eyes 14, similar eyes 15, being positioned in the front element 11, and engageable in the eyes 14 are snap hooks 16 formed near the 55 outer ends of an inflatable, cushion element 17 from which extend straps 19 cross con-

nected by a band 20 near their outer ends, in which are secured rings 21, and a pair of similar snap hooks 22 engageable in the front eyes 15.

60 Formed near the bottom of the block 10, is a longitudinal slot 24, and transversely disposed through the wider portion of the block is a shaft 25, and fixed midway in its length, within the slot 24, is a sprocket 26, over which is trained a chain 27, passing 65 over a similar but larger sprocket wheel 28, mounted on a spindle 29, rotatably mounted transversely in the narrow part 11 of the saddle, the extending ends of the spindle 70 having secured upon them cranks 30, by which rotary motion may be communicated by the operator to the shaft 25.

The outer ends of the shaft 25, which are suitably journaled within the block 10, have 75 fixed upon them spur gears 32, meshing with spur pinions 33 fixed upon sleeves 34 rotating on studs 35 fixed in the upper portion of the saddle block 10, the construction being solidly bolted together by U bolts 80 36 passing through open slots 37 formed vertically through the block 10 and held in position by nut 38.

To the outer ends of the sleeves 34 are secured plates 40, the sleeves being held in operable position by nuts 41. Extending laterally out from the plates 40, are uniformly spaced pairs of paddles 42, the axis of rotation of the paddles being substantially 85 level with the surface of the water in which 90 the apparatus floats.

In operation, the person using the apparatus is disposed at length comfortably upon the cushion 17, previously inflated so as to 95 partially support the weight of the operator, who grasps the handles 30 and turning the same in an obvious manner, transmits power through the train of gears to the sleeves, causing the paddles 42 to operate in a manner which will be well understood.

100 These paddles act in a manner similar to the paddle wheels of a steamer, one pair being distributed on each side thereof, in such manner as to propel the apparatus through the water at a rate of speed commensurate 105 with the power exerted upon the handles 30.

From the foregoing it will be seen that a safe and easily operated appliance materially assisting swimmers in propelling themselves through the water has been disclosed, which may be used for various 110 sports, help a person to swim a very consid-

erable distance, and as a life saving apparatus.

Having thus described my invention what I claim as new and desire to secure by Letters Patent, is—

- 5 1. In a swimming apparatus, the combination with a saddle shaped floating block and a pneumatic cushion engaged therewith adapted to receive the person in a recumbent position thereon, a shaft journaled transversely in said block, a pair of manually operable cranks in the forward end of said block, connections between said cranks and said shaft, and pairs of laterally extending paddles adapted to rotate in a longitudinal axis, the axis of said paddles being substantially level with the surface of the water in which said apparatus floats.
- 10 2. In a swimming apparatus, the combination with a saddle shaped buoyant block having a narrow extending front portion,
- 15
- 20

of a pair of cranks journaled in the front portion of said block, a sprocket engaged upon said crank shaft, means for manually operating said crank shaft, a shaft journaled transversely in the rear of said block, 25 a sprocket secured thereto, chains communicating motion between said sprockets, gears secured to the extending ends of said shaft, studs fixed in said block, above said shaft, sleeves rotatably mounted on said studs, pinions on said sleeves engaging with said gears, plates rigidly secured upon the outer ends of said sleeves, and pairs of paddle wheels extending outward from said plates, 30 said paddle wheels being adapted to rotate upon a horizontal axis when motion is communicated to said cranks.

In testimony whereof I have affixed my signature.

FEDKO FEDZYNA.
